OSSIP JOSEPH WALINSKY, OF SEA GATE, NEW YORK

HAT BOX

Application filed August 24, 1927. Serial No. 215,010.

This invention relates to hat boxes such as now commonly used for traveling purposes, and has for its object to provide a hat box wherein the space occupied by the cover or lid may be more conveniently and satisfactorily utilized; to enable garments and the like to be retained in the cover or lid when the same is opened or closed; to provide a garment hanger in the hat box and supported therefrom; to mount said garment hanger on the cover or lid; to provide a garment hanger which may be removed from the hat box; to adapt the support of the garments in the hat box to the contour of the hat box so as to utilize the space to best advantage; to secure simplicity of construction and operation; and to obtain other advantages and results as may be brought out in the following description.

20 Referring to the accompanying drawing in which like numerals of reference indicate similar parts throughout the several views;

Figure 1 is a perspective view of a hat box embodying my invention; and

25 Figure 2 is a sectional view on line 2—2 of Fig. 1.

In the specific embodiment of the invention illustrated in said drawing, the hat box preferably comprises a body or main receptacle 1 which may be of any suitable configuration but is usually substantially circular in cross-section with a flattened portion upon which the box may rest diametrically opposite to a handle 2 by which the box may be carried.

30 The body of the box, around its open side, is provided with a projecting rim 3 of slightly less exterior diameter than the box. A cover 4 is hinged to the flattened portion of the body

40 of the box and is adapted to close down over said rim 3. Suitable locks or catches 5 are provided to retain the cover closed down upon the body, as is usual in construction of hand luggage. Likewise, suitable means,

45 such as ribbons or straps 6 are provided to limit the swinging open of the cover to substantially a position perpendicular to its closed position. When the hat box is being packed or unpacked, it is usually laid down in the position shown in Figure 1 and the cover

opened so it assumes a substantially upright or vertical position.

The cover 4 as usually employed in connection with hat boxes constitutes a disc-like body portion 7 with a substantially circular 55 rim 8 projecting perpendicular from the edge of the body. Heretofore in packing hat boxes, the space within the bag provided by this rim has to be accounted for by packing an excess in the body of the bag, so that packing and 60 closing the bag is made that much more difficult. In the present invention I provide means for packing articles directly in the cover to utilize the space provided by the rim around the cover without having to pile the 65 goods first into the body of the bag. I preferably mount a suitable bracket 9 on the inside wall of the rim 8 of the cover, this bracket being positioned diametrically opposite to the hinging of the cover so it will be 70 at the uppermost part of the rim when the cover is opened. While I have shown this bracket as permanently attached to the rim, I deem it within the scope of the invention to secure it otherwise, if found more desirable. 75

This bracket preferably provides a suitable means for mounting thereon a garment hanger 10. In the present showing I provide a loop 11 on the garment hanger and a hook 12 on the bracket, but obviously here again the 80 construction may be altered if found to be more desirable otherwise. The garment hanger provides a very ready means for applying various garments both to the shoulders 13 thereof and to the cross-bar 14 extending 85 between the lower ends of said shoulders 13. The shoulders 13 of the hanger 10 are sloped downwardly away from the central support or loop 11 so as to not only properly support garments thereon but to follow the same 90 general direction of the curved rim so as to enable garments to be hung on the hanger and substantially fill the space between the hanger and the rim. After the garments are placed on the hanger, the hanger is inserted in the cover of the hand bag and mounted on the supporting bracket 9. The lower ends of the garments, if the same have not already been folded to adequate size, may then be folded 95 to lie within the cover and the lower portions 100

of the garments are secured against swinging out from the cover by suitable retaining means 15. As herein illustrated said retaining means comprises a pair of ribbons or straps secured to opposite points of the cover next to the rim in a chordal direction and shown as adapted to be buttoned together at their inner ends to confine the garments between said ribbons and the body of the cover. I accordingly provide not only a simple, but efficient means for packing goods within a cover of a hat box, and render the space available for neat packing of the goods and retaining of them in position while the cover is swung closed or opened.

Obviously detail changes and modifications may be made in the construction and use of my invention, and I do not wish to be understood as limiting myself to the exact construction shown or described, except as set forth in the following claims when construed in the light of the prior art.

Having thus described my invention, I claim:

- 25 1. A hat box comprising a body having a cover hinged thereto, and means for mounting a garment hanger on the edge wall of said cover at the side thereof opposite to the hinging of said cover to the body portion.
- 30 2. A hat box comprising a body having a cover hinged thereto, a garment hanger bracket in said cover on the edge wall thereof, and a garment hanger adapted to be supported by said bracket.
- 35 3. A hat box comprising a body having a cover hinged thereto, means on the edge wall of said cover for mounting a garment hanger in said cover at the side thereof opposite to the hinging of said cover, and means for retaining garments supported by said hanger from swinging out of the cover when said cover is swung.
- 40 4. A hat box comprising a body having a cover hinged thereto, means for mounting a garment hanger on the edge wall of said cover at the side thereof opposite to the hinging of said cover, and straps extending across said cover inside the same for retaining garments supported by said hanger from swinging out of the cover when said cover is swung.

OSSIP JOSEPH WALINSKY.
